UNITED STATES PATENT OFFICE.

FREDERICK GEOFFREY LEES JOHNSON, OF WESTMINSTER, LONDON, ENGLAND, AS-
SIGNOR TO VICKERS LIMITED, OF WESTMINSTER, ENGLAND, A BRITISH COMPANY.

HIGH-EXPLOSIVE SHELL.

Application filed February 6, 1924. Serial No. 690,922.

To all whom it may concern:

Be it known that I, FREDERICK GEOFFREY LEES JOHNSON, a subject of the King of Great Britain, residing at Vickers House, 5 Broadway, Westminster, in the county of London, England, have invented certain new and useful Improvements in or Relating to High-Explosive Shells, of which the following is a specification.

This invention relates to high explosive shells and has for its chief object to provide a more sensitive and reliable ignition than is given by the existing base fuzes while retaining the advantages resulting 15 from the base ignition of the explosive charge.

According to the invention the ignition device comprises an impact or percussion fuze at or near the nose of the shell, a detonator at or near the base of the shell and a tube or channel by which the flash from the fuze is transmitted to the detonator. In small shells the said tube may be inserted from the front of the shell, the 20 nose-piece carrying the impact or percussion fuze being screwed into position after the shell has been loaded with its high explosive charge and the tube has been placed in position, or the said tube may be inserted 25 from the base of the shell. In large armour-piercing shells the tube is carried by the usual base plug which closes the opening through which the explosive charge is inserted into the shell and the aforesaid impact or percussion fuze may be attached to the front end of the armour-piercing cap, the latter being formed with an axial hole 30 through which and through an axial hole in the head of the shell, the flash from the percussion cap passes to the tube and thence to the detonator.

In order that the said invention may be clearly understood and readily carried into effect, the same will now be more fully described with reference to the accompanying drawings, in which:—

Figures 1, 2 and 3 are axial sections shewing three constructional forms of the the invention as applied to small shells, Figures 50 1 and 2 illustrating two pounder shells for example and Figure 3 illustrating an eighteen pounder shell.

Figure 4 is a view similar to Figures 1, 2 and 3, but with the wind or contour cap in 55 elevation, shewing a form of the invention

as applied to an armour-piercing shell of large calibre, and

Figure 5 is an axial section, drawn to a larger scale, of the wind or contour cap of Figure 4 and the parts of the fuze disposed therein.

A is the shell, B, B¹ respectively are the needle or striker and the percussion cap of the impact or percussion fuze and C is the axial tube by which the flash from the fuze 60 is transmitted to the detonator C¹ carried in the rear part of the said tube. In all the constructions shewn the fuze is generally similar to that forming the subject of the prior English Patent No. 180,422, the needle 65 B and the percussion cap B¹ being carried by piston-like elements B^x, B^{1x} respectively the rear surfaces of which are subjected to the pressure of the air during the flight of the shell in order to move both these elements in a forward direction after they have been unlocked by suitable inertia and centrifugal devices. The needle B forms 70 part of a member B² which, when the element B^x is moved forwardly as aforesaid, projects beyond the nose of the shell so that on impact of this member with an obstruction the needle B is forced against the percussion cap B¹ the holder of which is suitably retained in its operative or forward 75 position.

In the construction shewn by Figure 1 the tube C with the detonator C¹ in position is inserted from the open front of the shell with its rear end disposed around a central 80 projection on a disc D disposed in the lower end of the cavity in the shell. The charge E of tetryl and the charge F of T. N. T. are then inserted and a washer G is placed above them and secured by a screw g, this washer having a shouldered hole in which the upper end of the tube C is disposed. The fuze body H is then screwed into place, this body and the aforesaid member B² being 85 covered by tin foil h having a tear-off wire by which the tin foil can be stripped off when desired. A thin tube c of cardboard is employed for retaining the detonator in position.

The construction according to Figure 2 105 is generally similar to Figure 1 except that the tube C is screwed into an extension C^x having a flange of similar shape to the disc D of Figure 1. The rear end of the extension C^x is closed by a plug c^x after its in- 110

terior has been filled with an exploder C^{xx} composed for example of tetryl pellets.

In the construction according to Figure 3 the tube C and extension C^x are similar to Figure 2 but the extension C^x is screwed into a plug C² which screws into the base of the shell, the unit composed of the plug C², the extension C^x and the tube C being inserted from the rear and the opening 10 therein closed by a screw-threaded disc C³. In this construction the charge F of T. N. T. is contained in a paper container f.

In the construction according to Figures 4 and 5 the tube C and the extension C^x are connected by an internally screw-threaded extension of the plug C² which in this case is carried by another screw-threaded plug C⁴ closing the opening through which, in this construction, the charge F in its container f is inserted into the shell from the rear. Below the said charge F is a moulded block F^x of high explosive. The front end of the tube C communicates with an axial hole a passing through the nose of the shell. 25 This hole in turn communicates with an axial hole a¹ formed in the usual armour-piercing cap A¹ and the latter hole communicates with the magazine of the fuze. The fuze body H is attached to the front end 30 of the armour-piercing cap as shewn in Figure 5 and this cap also carries a casing A² having a ring a² against which bears a shoulder a³ on the wind or contour cap A³. The forward end of the said casing A² is 35 screw-threaded to receive a screw-threaded member A⁴ bearing against the front end of the cap A³ as shewn. The forward part

of the casing A² supports a guide tube a⁴ in which the aforesaid member B² connected to the member R^x of the needle B is slidably 40 arranged.

What I claim and desire to secure by Letters Patent of the United States is:—

1. In a high explosive shell, the combination of an impact or percussion fuze at the nose of the shell, a high explosive charge within the shell, a gaine or detonator arranged contiguous to the rear part of said high explosive charge, and an axial tube by which the flash from the fuze is transmitted 50 to said gaine.

2. In a high explosive shell, the combination of an impact or percussion fuze at the nose of the shell, a high explosive charge within the shell, a gaine or detonator arranged contiguous to the rear part of said high explosive charge, an axial tube by which the flash from the fuze is transmitted 55 to the gaine, said tube being inserted from the base of the shell, and a plug carrying 60 said tube and closing the hole in the base.

3. In a high explosive shell, the combination of an impact or percussion fuze having a striking member situated at the nose of the shell, means for moving said member forward to arm the fuze by the air pressure created by the passage of the shell through the air, a high explosive charge within the shell, a gaine or detonator arranged contiguous to the rear part of said 70 high explosive charge, and an axial tube by which the flash from the fuze is transmitted to said gaine.

FREDERICK GEOFFREY LEES JOHNSON.
